The ornamental design for an animal medical alert vest-seizure, as shown and described.

DESCRIPTION

FIG. 1 is a perspective view of an animal medical alert vest-seizure showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken line showing of the dog in FIG. 1 is included for the purpose of illustrating environment that forms no part of the claimed design.

The dashed lines on the animal medical alert vest-seizure in FIGS. 1 through 3 are understood to represent stitching.
